W. U. Snyder

BY *Fred M. Bond*

ATTORNEY.

UNITED STATES PATENT OFFICE.

ULIDES SNYDER, OF LOUISVILLE, OHIO.

CAR-COUPING.

SPECIFICATION forming part of Letters Patent No. 431,728, dated July 8, 1890.

Application filed May 16, 1890. Serial No. 352,023. (No model.)

To all whom it may concern:

Be it known that I, ULIDES SNYDER, a citizen of the United States, residing at Louisville, in the county of Stark and State of Ohio, 5 have invented certain new and useful Improvements in Car-Couplings; and I do hereby declare that the following is a full, clear, and exact description of the same, reference being had to annexed drawings, making a part to of this specification, and to the letters of reference marked thereon, in which—

Figure 1 is an isometrical view showing the link properly attached to the draw-head. Fig. 2 is a longitudinal section of a draw-head, 15 showing the coupling-pin placed in position to be received through the link. Fig. 3 is a detached view of the gravity-block. Fig. 4 is a detached view of the pivoted catch-bar.

The present invention has relation to car- 20 couplings; and it consists in the different parts and combination of parts hereinafter described, and particularly pointed out in the claims.

Similar letters of reference indicate cor- 25 responding parts in all of the figures of the drawings.

In the accompanying drawings, A represents the draw-head, which is attached to the car in the ordinary manner. To the front or for- 30 ward end of the draw-head A is pivotally at- tached the catch-bar B, which is substantially of the form shown in Fig. 4, and, as shown, it is provided with the partition or connecting- bar a, which is for the purpose of holding the 35 pin C in an elevated position, as illustrated in Fig. 2. The gravity-block is located within the draw-head, and is held in the desired position by means of the extensions D and E. The extension E is located substantially 40 as illustrated in Fig. 2, and is received in the groove b. The front or forward ends of the gravity-block F rest and bear upon the free ends of the catch-bar B for the purpose of pressing down the free ends of the catch-bar 45 when the link G has been properly inserted into the draw-head, and thereby prevent the link from sagging.

The operation of my coupler is as follows: When it is desired to make a coupling, the pin

C is placed in the position shown in Fig. 2, 50 and as the catch-bar B is elevated at its free end the pin C will be thrown from its resting-place and fall through the link and the aperture c, thereby properly coupling the draw-heads together. To the catch-bar B is at- 55 tached the rod d, which extends up through the draw-head, and is for the purpose of adjusting the link G up or down at its free end by elevating the catch-bar B and removing the pressure of said catch-bar from the inner 60 end of the link. It will be understood that by resting the front or forward ends of the gravity-block F on the free ends of the catch-bar B the front or forward end or portion of said gravity-block will be elevated as 65 the catch-bar B is elevated by the link, and at same time said gravity-block will not interfere with the movements of said catch-bar B. It will be also understood that if desired the operating-rod d may extend upward to 70 the top of cars, thereby enabling a brakeman to guide the link G into the draw-head, thereby preventing the necessity of entering between the cars to make a coupling.

Having fully described my invention, what 75 I claim as new, and desire to secure by Letters Patent, is—

1. The combination of the draw-head A, having pivotally attached thereto the catch-bar B, provided with the partition a, the gravity-block F, located within the draw-head, the extensions D and E, the pin C, and the link G, substantially as and for the purpose specified.

2. The combination of the draw-head A, 85 having pivotally attached thereto the catch-bar B, the rod d, attached to said catch-bar, the gravity-block F, and the pin C, and the link G, substantially as and for the purpose specified.

In testimony that I claim the above I have hereunto subscribed my name in the presence of two witnesses.

ULIDES SNYDER.
